UNITED STATES PATENT OFFICE.

EUGENE M. NICHOLS, OF PHILADELPHIA, PENNSYLVANIA.

SCRAPING-MACHINE FOR FILTER-BEDS.

1,150,876.

Specification of Letters Patent. Patented Aug. 24, 1915.

Application filed March 1, 1915. Serial No. 11,408.

To all whom it may concern:

Be it known that I, EUGENE M. NICHOLS, a citizen of the United States, residing at Philadelphia, in the county of Philadelphia and State of Pennsylvania, have invented 5 certain new and useful Improvements in Scraping-Machines for Filter-Beds, of which the following is a specification.

My invention relates to improvements in 10 scraping machines for filter beds, the object of the invention being to provide a machine of the character stated which is adapted to be moved over a filter bed, and which will remove the sand from the surface of the 15 bed as the machine is moved over the bed.

A further object is to provide a machine 20 of the character stated having an endless movable combined scraper and conveyer positioned at an angle to the plane of the filter bed, and adapted to scrape the surface of the bed and convey the sand upwardly and rearwardly and deposit the same into a hopper from which it is discharged.

With these and other objects in view, the 25 invention consists in certain novel features of construction and combinations and arrangements of parts as will be more fully hereinafter described and pointed out in the claims.

30 In the accompanying drawings: Figure 1 is a view in side elevation illustrating my improved machine. Fig. 2 is a view in section through the combined scraper and conveyer, the section taken on the line 2—2 of Fig. 1, other parts of the machine being omitted for purposes of clearness. Fig. 3 is a top plan view of the machine showing a part of the conveyer casing broken away. Fig. 4 is a view in elevation showing my 35 improved separator detached, and Fig. 5 is a view at right angles to Fig. 4.

1, 1, represent boards which are laid upon the filter bed 2, and serve as tracks upon which the wheels 3 of my improved machine 45 are adapted to move.

4 is the frame of the machine supported on axles 5 mounted in the wheels 3, and on the frame 4 a separator 6 is located and is connected by a pipe 7 with the lower end of 50 a hopper 8.

A water jet is utilized to convey the sand from the bottom of the hopper 8 through the pipe 7 into the separator 6, and 9 represents the water supply pipe for this jet.

55 The details of the separator and the co-operating parts form no part of the present invention, and hence need not be described

in detail, except to say that they care for the sand which is deposited in the hopper by my improved conveyer 10 which will now be described in detail. The conveyer 10 comprises an endless flexible member which may consist of a belt as illustrated, having a series of blades 11 secured thereto and projecting at right angles therefrom. The conveyer 10 is supported upon three pulleys 12, 13, and 14, so that it assumes a general triangular shape, and is positioned at an angle to the filter bed as shown clearly in Figs. 1 and 3. The several runs of the conveyer 15 vary in length. The front and lower run 15 of the conveyer extends transversely across the front of the machine, with the blades or vanes located at an angle so that their lower corners operate to cut into the 20 filter bed and carry the sand to the side of the machine, the conveyer moving in the direction of the arrow. This front run of the conveyer is strengthened by a backing plate 16 which holds the scrapers up to their work, and relieves the belt of undue strains. The run 17 of the conveyer, between pulleys 12 and 13, is in a general upward and rearward direction, and through a tubular casing 18 which extends partially around the 25 pulley 12 at its lower end, which lower end constitutes an entrance into which the sand is carried by the blades 11 of the conveyer. The bottom of this tubular casing 18 is open as shown at 19 where it rounds the pulley 30 13, and this opening 19 communicates with the hopper 8, so that the sand which is carried up the tubular casing 18 is dropped into the hopper by the blades 11. The run 20 of the conveyer, between pulleys 13 and 14, is preferably incased as shown at 21 to 35 house the conveyer and prevent injury thereto.

While my invention is not limited to any power transmission means, I have illustrated a motor 21 supported on the frame 4, and driving a pulley 22, which latter is connected by a belt 23 with a pulley 24 on a shaft 25. The shaft 25 is supported in a bracket 26, and in a bearing 27 on the casing 18, and at one end is provided with a beveled pinion 28 meshing with a beveled gear 29 on the shaft 30, to which pulley 13 is secured, so that by reason of the mechanism above described, the conveyer is operated at the 40 desired speed. It is also to be understood that the machine will be moved over the filter bed in accordance with the work as it is performed, and this movement of the ma-

chine may be accomplished in any desired manner.

A represents the discharge pipe for the dirty water after the clean sand has been 5 precipitated in the separator and discharged through pipe B, thereby performing the entire work of scraping, removing and depositing the clean sand on the filter bed, approximately in its original position, 10 without removing from the inclosure of the filter. The details of the separator and coöperating parts are fully described in my former Patent No. 936,801 dated October 12, 1909, and need not be described in de- 15 tail.

In operation, as the machine moves over the filter bed, the conveyer blades 11 as they move transversely of the machine along the run 15 of the belt, scrape the filter bed and 20 convey the sand into the lower end of casing 18, then up the casing 18, through the opening 19 into hopper 8 from which it is discharged through the pipe 7 into separator 6, as above explained. The operation 25 therefore of scraping and conveying is a continuous one, and is performed by a single endless conveyer, and while I have referred to the conveyer as a belt, it is to be understood that I may employ other forms of 30 endless flexible mechanism for supporting the blades, and do not limit myself to the precise details of construction, but consider myself at liberty to make such changes and alterations as fairly fall within the 35 spirit and scope of the appended claims.

Having thus described my invention, what I claim as new and desire to secure by Letters Patent is:

1. The combination with a frame, of a 40 combined transverse scraper and elevating conveyer, comprising a single unit supported on the frame, and located at an angle there- to, substantially as described.

2. The combination with a horizontal 45 frame, wheels supporting the frame, and a combined elevating conveyer, comprising a single unit and transverse scraper located at an angle to the horizontal frame, substan- tially as described.

50 3. In a machine of the character de- scribed, the combination with a frame, wheels supporting the frame, and a com- bined elevating conveyer and transverse scraper comprising a single unit located at 55 an angle to the frame and having its front run located at the front of the frame and movable transversely of the frame, substan- tially as described.

60 4. In a machine of the character de- scribed, the combination with a frame, and wheels supporting the frame, of an inclined tubular casing supported on the frame, and an endless conveyer movable through the

tubular casing and across the front of the machine, substantially as described. 65

5. In a machine of the character de- scribed, the combination with a wheeled frame, and a hopper on the frame, of a plu- rality of pulleys supported on the frame, an 70 endless conveyer on the pulleys, said con- veyer having a series of blades thereon, a tubular casing through which one run of the conveyer moves, said tubular casing at one end communicating with the lowest point of the conveyer and at its other end 75 communicating with the hopper, substan- tially as described.

6. In a machine of the character de- scribed, the combination with a wheeled frame of an endless combined scraper and 80 conveyer comprising a single unit located at an angle to the frame and having one run of the conveyer extending across the front of the frame, substantially as described.

7. A scraping machine for filter beds 85 comprising a wheeled frame, and a com- bined scraper and conveyer supported on the wheeled frame and having a series of blades or vanes thereon, said combined 90 scraper and conveyer located at an angle to the filter bed and having its front run ex- tending across the front of the frame with the blades at an acute angle to the filter bed, whereby the lower corners of the blades cut 95 into the filter bed, substantially as described. 95

8. A scraping machine for filter beds comprising a wheeled frame, and a com- bined scraper and conveyer supported on the wheeled frame and having a series of blades or vanes thereon, said combined 100 scraper and conveyer located at an angle to the filter bed and having its front run ex- tending across the front of the frame with the blades at an acute angle to the filter bed, whereby the lower corners of the blades cut 105 into the filter bed, a hopper on the frame, a tubular casing inclosing a run of the conveyer, and extending from the filter bed up to the upper end of the hopper, sub- stantially as described. 110

9. In a machine of the character de- scribed, a combination of a wheel frame, of a combined scraping conveyer, a hopper connecting with a liquid supply and dis- charge for sand and liquid, a separator to 115 separate the clean sand from the dirty water and foreign matter and depositing said clean sand on the bed.

In testimony whereof I have signed my name to this specification in the presence of 120 two subscribing witnesses.

EUGENE M. NICHOLS.
